SAFE OR MONEY CHEST

William C. Miller, Canton, Ohio, assignor to
Diebold Safe & Lock Company, a corporation
of Ohio

Application June 6, 1932, Serial No. 615,698

2 Claims. (Cl. 109—1)

The invention relates to safe or money-chests, and particularly to a safe or money-chest in which the daily receipts of stores, theaters, etc., may be placed temporarily for safe keeping.

5 A safe or money-chest of this type is shown in the co-pending application, Serial No. 511,893, filed January 28, 1931, now Patent No. 1,965,296, issued July 3, 1934.

One form of the present invention is embodied 10 in a safe or money-chest of the type described which comprises a heavy walled container or housing preferably formed from cast metal, the container being embedded in a block of concrete formed in a sheet metal shell. In this form of 15 the invention, access is had to the interior of the container through the open top thereof which is provided with a heavy door rotatably mounted in a plate pivoted to the container. The container is divided into upper and lower compartments, 20 the lower compartment being provided with a separate door or closure member having a lock which requires two keys for its operation. The door for the lower compartment carries auxiliary locking means so that if the lock on it is forced 25 out of place, an auxiliary locking bolt will lock the door to the housing. The container is provided with an integral ring or flange from which a money bag may be suspended in the lower compartment. The upper compartment is adapted 30 to hold funds over night to provide change for doing business the next day. The lower compartment is adapted to hold the major portion of the receipts which may be passed into it through a slot formed in the heavy wall of the container 35 and extending between the compartments.

Other advantages will become apparent as the following detailed description progresses, reference being had to the accompanying drawings, wherein

40 Figure 1 is a vertical section taken through a device which embodies the invention, the money-chest or container proper being shown in elevation.

Fig. 2 is a plan view of the device shown in 45 Fig. 1.

Fig. 3 is an enlarged section taken on line 3—3 of Fig. 2.

Fig. 4 is a plan view of the container or money-chest proper, the outer door being omitted to illustrate other details of construction.

Fig. 5 is a section taken on line 5—5 of Fig. 3.

Fig. 6 is an enlarged section taken on line 6—6 of Fig. 2.

Fig. 7 is a bottom view of the outer door or 55 closure member.

Fig. 8 is a fragmentary section taken on the same line as Fig. 6, the outer door or closure member being omitted to illustrate certain details of construction.

Fig. 9 is a bottom view of the inner door or 5 closure member for the lower compartment.

Fig. 10 is a section taken on line 10—10 of Fig. 9, a portion of the wall of the container being shown.

Fig. 11 is a section taken on the same line as 10 Fig. 10, but showing certain parts in changed positions, and

Fig. 12 is a fragmentary plan view of the lock for the inner door or closure member.

Referring to the drawings wherein a money- 15 chest which embodies a preferred form of the invention is shown, A designates a block of concrete; B, a sheet metal shell which houses the block A; C, the money-chest proper; D, an upper compartment in the money-chest adapted to hold 20 money over night and accessible to the owner of the store, or the like, in which the money-chest is placed; E, a lower compartment in which money in excess of what is needed to conduct the business is placed for safe keeping; F, a door or closure 25 member for the door opening in the money-chest proper; G, a door or closure member for the lower compartment E, which door G serves as a partition wall between the two compartments; and H, a bag adapted to be suspended in the lower 30 compartment E to hold the money which is deposited in the lower compartment.

The concrete block A is preferably formed in a sheet metal shell B at the place the improved device is to be installed. In some instances, however, the device will be completely fabricated before it is shipped to the store, or the equivalent, in which it is to be installed. The sheet metal shell B may be of any suitable size and shape.

The money-chest C preferably comprises an 40 integral heavy walled container 10 which is preferably a steel casting. The container 10 is embedded in the concrete block A and it will be noted that it is of such shape that it cannot be removed therefrom without cutting or breaking away a 45 large portion of the block.

The container 10 comprises an annular flange 11 at its upper end, which flange rests upon the upper wall of the sheet metal shell B. The container 10 is open at its top and is provided with 50 a frusto-conical surface 12 which is engageable by a similar surface formed on the door or closure member F. Projecting inwardly from the frusto-conical surface 12 are a plurality of lugs 13 which provide bayonet slots for lugs formed 55

upon the door F. As best shown in Figs. 4 and 6, the wall of the container 10 is provided with a recess 15 which is engageable by a bolt or a lock provided on the door F. The container 10 is provided with relatively narrow integral flanges 16 and 17 intermediate the upper and lower compartments D and E, respectively, which flanges 16 and 17 provide an annular groove 18 engageable by locking bolts of the door or closure member G. An annular bead or flange 20 formed integral with the container 10 below the flanges 16 and 17 is adapted to support the bag H which is suspended therefrom.

A slot 22 is formed in the wall of the container 10 and extends from the compartment D to the compartment E, the slot 22 being of such shape and size that one cannot reach therethrough with instruments to extract money from the bag H. It will be noted that the lower end of the slot 22 opens into the compartment E just above the mouth of the bag H. The upper end of the slot 22 is not accessible when the closure member F is in its closed position.

The closure member F preferably comprises a body portion 25 formed from cast steel. As stated above, it has a frustro-conical surface which engages the frustro-conical surface 12 when it is in its closed position. The lower end of the closure member F is of reduced diameter and is also provided with a frustro-conical surface which is identified by the reference character 26. Projecting from the frustro-conical surface 26 and formed integral with the body portion 25 are a plurality of lugs 27 which, when the closure member is being brought into its closed position, pass through the spaces between the lugs 13 into positions from which they may be angularly displaced to lie beneath the lugs 13. When the lugs 27 are disposed beneath the lugs 13 it is, of course, impossible to withdraw the closure member F from the container until the closure member has been angularly displaced to align the lugs 26 with the spaces between the lugs 13. A pin 25a limits such angular displacement of the closure member F, the pin 25a being adapted to engage two of the lugs 13. (See Figs. 5 and 7.)

The closure member F is provided with an upwardly extending integral boss 28 which is journaled in a plate 29 pivoted on a pin 30, the ends of the pin 30 being mounted in blocks 32 which are secured to the body portion 25 by bolts 33, or the equivalent. This construction permits the closure member F to be swung from its closed position to the position wherein it is shown in dotted lines in Fig. 6.

Secured to the top surface of the closure member F by a bolt 35 is a handle member 36 which one may use to angularly displace the closure member in the plate 29 to bring the lugs 27 into and out of their locking positions beneath the lugs 13. Such angular displacement of the closure member F is limited by a bolt 38 which is screw threaded into the closure member and rides in an arcuate slot 39 formed in the bolt 29. The length of the slot is such that when the bolt 38 is at one end thereof, the lugs 27 will be in registry with the lugs 13 and when the bolt is at the other end of the slot, the lugs 27 will be in registry with the slots or spaces between the lugs 13.

Any suitable lock may be provided for the closure member F, but I preferably provide a combination lock 40 disposed in a recess 41 formed in the bottom surface of the body portion 25. The lock 40 is provided with a spindle 42 which

extends to the usual knob and dial 43. Interposed between the bottom of the body portion 25 and the lock 40 are a plurality of layers 44 of chromium steel or any other drill-proof metal, the layers 44 being provided with apertures through which the spindle 42 passes. The drill-proof layers 44 prevent unauthorized persons from gaining access to the compartment D by drilling through the body portion 25 into the lock 40.

The lock 40 is secured to the body portion 25 by screws 47, or the equivalent. A back plate or dished pan 49 secured to the bottom surface of the body portion 25 serves as a closure member for the recess 41 in which the lock 40 is disposed. As best shown in Fig. 6, the bolt 46 comprises a bolt 50 which is engageable with the recess 15. The construction is such that the bolt 50 is in registry with the recess 15 when the lugs 27 are in their locking positions. Obviously, when the bolt 50 engages the recess 15, the body portion 25 cannot be angularly displaced and access cannot be had to the compartment D until the combination lock 40 has been manipulated to retract the bolt 50.

The closure member G preferably comprises a disc 52 having an annular flange 53 adapted to rest upon the upper surface of the flange 16. A pair of pins 54 which project from the periphery of the disc 52 extend into the groove 18 when the closure member G is in its closed position. A lock 56 secured to the bottom surface of the disc 52 by screws 57 comprises a bolt 58. A pin 59 projecting upwardly from the bolt 58 rides in a slot 60 formed in the disc 52 and engages a bolt 62 slidably journaled in a bore 63 formed in the disc 52. When the lock 56 is in its locked condition, the bolts 58 and 62 occupy the positions wherein they are shown in Fig. 3 so that the bolt 62 extends into the groove 18. Obviously, when the bolt 62 extends into the groove 18, it co-operates with the pins 54 and locks the closure member G to the flange 16. When the lock 56 is unlocked, the bolt 58 is retracted and it, in turn, retracts the bolt 62 from the groove 18 so that one may tilt the closure member G around the point at which the pins 54 project from the disc 52 and then disengage the pins 54 from the groove 18. The closure member G may then be removed from the container. A handle 52a is provided for this purpose.

The lock 56 is preferably of the type which must be manipulated by two keys. Thus, as shown in Figs. 3 and 4, the lock 56 is provided with key barrels or plugs 65 and 66 which extend through the disc 52. In practice, one of the keys is retained by one who is generally on the premises and the other key is retained by one who comes to collect funds deposited in compartment D. Thus, the latter key may be in the possession of a company which has its agents collect these funds at a certain time each day and then deposits the money in a bank.

Referring now to Figs. 9 to 12, inclusive, it will be noted that the disc 52 is provided with a bore 70 in which an auxiliary locking bolt 71 is slidably journaled, the bolt 71 being aligned with the groove 18 when the closure member G is in its closed position. The bolt 71 is provided with an annular groove 73 into which a pin 74 projects, the pin 74 being secured to the lock 56. Intermediate the inner end of the bolt 71 and the bottom surface of the bore 70 is a compression spring 75 which is normally under tension. If an attempt is made to gain access to the compartment E by driving the lock 56 off the bottom surface

of the disc 52 as illustrated in Fig. 11, the pin 74 will be withdrawn from the annular groove 73 so that the spring 75 will drive the auxiliary bolt 71 into the groove 18. This will relock the closure member G. It may be mentioned that such displacement of the lock 56 relative to the disc 52 is generally obtained by driving in the key barrels or plugs 65 and 66.

The upper end of the bag H is preferably secured to a ring 77 adapted to rest upon the bead or flange 20 as illustrated in Fig. 3. In this instance, the bag H is provided with a closure portion 78 which may be folded back as shown in Fig. 3. When the bag is removed from the container 10 the closure member may be drawn over the top of the bag and a seal (not shown) may be inserted through the eyelets 79 provided in the closure portion 78.

The size and weight of the block A are preferably such that it can be readily removed from the premises in which it is placed. The dimensions of the container 10 are such that the slot 22 and the inner compartment E are within hand-reach from the top of the container.

While I have shown and described certain embodiments of my invention, it is to be understood that it is capable of many modifications. Changes, therefore in the construction and arrangement may be made without departing from

the spirit and scope of the invention as disclosed in the appended claims, in which it is my intention to claim all novelty inherent in my invention as broadly as possible, in view of the prior art.

5

I claim:

1. A deposit-safe comprising: an anchor block; a heavy-walled container embedded in said block and having a change-cash compartment therein and a surplus-cash compartment accessible 10 through said change-cash compartment, said container being provided with an annular inwardly extending rib in said surplus-cash compartment for holding a money-bag, the wall of said container being provided with a slot extending from 15 said change-cash compartment to said surplus-cash compartment above said annular rib.

2. A deposit-safe comprising, an anchor block, a heavy-walled container imbedded in said block and providing an upper change-cash compartment 20 and a lower surplus-cash compartment, a removable closure for said lower compartment and forming the bottom of said upper compartment, a small curved passage extending through the wall of the container from the upper portion 25 of the change-cash compartment and opening into the upper portion of the surplus-cash compartment.

WILLIAM C. MILLER.
